UNITED STATES PATENT OFFICE

106,451

DESIGN FOR A RADIATOR GRILLE FOR AN AUTOMOBILE

John Oswald, Lansing, Mich., assignor to General Motors Corporation, Detroit, Mich., a corporation of Delaware

Application July 12, 1937, Serial No. 70,374

Term of patent 3½ years

To all whom it may concern:

Be it known that I, John Oswald, a citizen of the United States and a resident of Lansing, county of Ingham, and State of Michigan, have invented a new, original, and ornamental Design for a Radiator Grille for an Automobile, of which the following is a specification, reference being made to the accompanying drawings forming a part thereof.

Figure 1 is a front view of the radiator grille showing my new design.

Figure 2 is a side view.

Figure 3 is an enlarged section on the line 3—3 of Figure 2, the view being a half section only of what is indicated on the section line 3—3.

I claim:

The ornamental design for a radiator grille for an automobile, as shown.

JOHN OSWALD.
